United States Patent Office

Des. 210,991
Patented May 14, 1968

210,991

SNACK FOOD PRODUCT

Duane D. Oelke, Wayzata, and Le Roy E. Gronberg, Minneapolis, Minn., assignors to General Mills, Inc., a corporation of Delaware

Filed June 22, 1967, Ser. No. 7,551

Term of patent 14 years

(Cl. D1—13)

FIG. 4

FIG. 2

We claim:

The ornamental design for a snack food product, substantially as shown.
